(57) **CLAIM**

The ornamental design for a locking cover for trailer hitch pins, as shown and described.

DESCRIPTION

FIG. 1 is a top, rear perspective view of a locking cover for trailer hitch pins;

FIG. 2 is a bottom, front perspective view of the locking cover for trailer hitch pins as in FIG. 1;

FIG. 3 is a rear, elevational view thereof;

FIG. 4 is a front, elevational view thereof;

FIG. 5 is a right-side, elevational view thereof;

FIG. 6 is a left-side, elevational view thereof;

FIG. 7 is a top plan view thereof; and,

FIG. 8 is a bottom plan view thereof.

The broken lines shown in the drawings illustrate portions of the locking cover for trailer hitch pins that form no part of the claim.
